UNITED STATES PATENT OFFICE.

HARRY WILLIAMS CHARLTON, OF OTTAWA, ONTARIO, CANADA.

WATER-CLOSET.

No. 900,831.

Specification of Letters Patent.

Patented Oct. 13, 1908.

Application filed August 5, 1907. Serial No. 387,228.

To all whom it may concern:

Be it known that I, HARRY WILLIAMS CHARLTON, of the city of Ottawa, in the county of Carleton, Province of Ontario, 5 Dominion of Canada, have invented certain new and useful Improvements in Water-Closets, of which the following is a specification.

My invention relates to improvements in 10 water closets, and the objects of my invention are to eliminate the unpleasant odors which at the present time escape during use and to render the means for effecting such elimination automatic in character. These 15 objects are carried out by automatically creating a current of air through the bowl of the closet during use, and in the embodiment illustrated this current is created by a fan operated by a water motor which is thrown 20 automatically into operation by means of a tilttable back.

Referring to the drawings, Figure 1 is a 25 side view of the closet partially in section. Fig. 2 is an enlarged sectional detail of the water motor. Fig. 3 is a sectional view on the line 2—2, Fig. 2. Fig. 4 is a view of the 30 underside of the seat. Fig. 5 is a longitudinal section thereof. Fig. 6 is an enlarged sectional detail of the end of the seat. Fig. 7 is a horizontal section through the 35 water wheel.

In the drawings, like letters of reference indicate corresponding parts in each figure.

In the drawings, A represents the bowl of 35 the closet suitably connected to the tank B provided with the usual flushing mechanism.

In accordance with my invention an 40 exhausting fan C is provided, located conveniently with regard to the bowl and adapted to exhaust the gases therefrom. In the embodiment illustrated the fan is located in the space above the water in the tank B and is connected to the bowl through the medium of a conduit a which communicates with a channel 45 running around the bottom of the seat and which is preferably covered by a plate c having perforations d therein. To equalize the flow of air around the bowl, the perforations towards the front thereof are 50 gradually enlarged as shown. The fan discharges through a conduit e into the ventilating pipe. While the exhausting fan may be operated by any suitable means, I prefer to employ a water motor, as this may be 55 conveniently operated by the supply of water for the closet.

The water wheel D is preferably directly connected to the shaft f of the fan C and has its outlet pipe emptying into the tank B. A valve h is provided in the supply pipe i 60 for the water motor and this valve is connected to a tilttable back rest E. This may be conveniently accomplished by securing the back to the spindle j of the valve. The back rest is normally held in its outermost 65 position by a tension spring k connected thereto and to a rod l extending transversely across the tank. To prevent the back rest exerting a continual pressure against the back of the user, and thus producing discomfort, a spring catch m is provided adapted to engage a projection n on the back rest, when the rest is in its innermost position. The catch m, as shown, is in the form of a U-shaped piece of narrow spring metal, under 70 which the projection n is adapted to spring and be retained in position. To enable the seat to be readily freed from the stop, the back rest is preferably pivoted to the spindle j whereby it may be swung laterally out 75 of engagement with the catch. When the back rest is swung about the pivot on the spindle j, the end n will be moved sidewise out of engagement with the narrow spring catch m, disengaging it therefrom, and permitting it to return to its normal position 80 under the action of the spring k.

As a further aid to the operation of the closet, I provide means for automatically operating the flushing mechanism when the 85 back rest is released. These means comprise a lever o secured to the spindle j and having an extension p connected thereto by a rule joint q and normally held in alignment with the lever by a spring r. The extension p is adapted, when the spindle is oscillated, by the tilting of the back, to engage the end of a lever s on the rod l, the opposite end of the lever being connected by a suitable chain t or other means to the flushing 95 mechanism (not shown). On its upward movement, the projection will itself tilt but on the downward movement it will oscillate 100 the lever.

In operation, the user tilting the back rest 105 opens the valve h which causes water to flow in through the inlet pipe i and thus rotate the wheel which operates the fan to draw the air and obnoxious gases from the bowl through the channel b and conduit a into the 110 ventilating pipe. To flush the closet, the user moves the back rest sidewise which dis-

engages it from the stop when the compression spring *k* tilts it to its first position, simultaneously shutting off the water from the water wheel and operating the flushing mechanism.

It will be observed that on the backward movement of the back rest the flushing mechanism is not affected as the rule joint permits the extension *p* to pass the end of the lever *s* without tilting the same. The water discharging from the motor into the tank, will be taken care of in the usual way.

The invention will successfully prevent the production of all bad odors in the rooms in which the closet is placed and greatly increase the hygienic efficiency of the closet.

While the invention has been described herein with great particularity of detail, it will be readily understood that in carrying out the same changes may be made in the details thereof without departing from the spirit of the invention.

What I claim as my invention is:—

1. In a water closet, the combination with the bowl and flushing tank therefor of a water motor discharging into the flushing tank, an inlet pipe therefor, a valve in the inlet pipe, a tiltable back, connecting means between the valve and the tiltable back, and means operated by the motor for creating a current of air in the bowl, lever connecting means between the same and the valve, a projection connected to the lever by a rule joint, a pivoted lever adapted to be tilted by the projection on the return movement of the first mentioned lever, and connecting means adapted to extend between the same and the flushing mechanism.

2. In a water closet, the combination with the bowl and flushing tank supported adjacent thereto, of a fan adapted to exhaust the bowl, a water motor for operating the same, a back rest tiltably supported from the tank, and a controlling valve for the water motor operated by the tilting of the back rest.

3. In a water closet, the combination with the bowl, flushing tank therefor and flushing mechanism, of a tiltable back rest, hydraulically operated exhausting means for the bowl, means operated by the backward movement of the back rest for throwing the exhausting means into operation and means operated by the forward movement of the back rest for operating the flushing mechanism.

4. In a water closet, the combination with the bowl, flushing tank therefor and flushing mechanism, of a tiltable back rest, hydraulically operated exhausting means for the bowl, means operated by the backward movement of the back rest for throwing the exhausting means into operation, means operated by the forward movement of the back rest, for operating the flushing mechanism, and means engaging the back rest and retaining it in its innermost position during use of the closet whereby the pressure on the back of the user may be eliminated.

5. In a water closet, the combination with the bowl, flushing tank therefor and flushing mechanism, of a tiltable back rest, hydraulically operated exhausting means for the bowl, means operated by the backward movement of the back rest for throwing the exhausting means into operation, means operated by the forward movement for operating the flushing mechanism, and a spring catch for retaining the back rest in its innermost position.

6. In a water closet, the combination with the bowl, flushing tank therefor and flushing mechanism, of a fan adapted to exhaust the bowl, a water motor operating the same, a back rest, means for supporting the same with freedom to tilt both forwardly rearwardly and laterally, means operated by the forward and rearward tilting for controlling the water motor, and the flushing mechanism, and means for retaining the rest in its innermost position adapted to be disengaged by lateral tilting.

7. In a water closet, the combination with the bowl, flushing tank therefor and flushing mechanism, of a fan adapted to exhaust the bowl, a water motor operating the same, a back rest, means for supporting the same with freedom to tilt both forwardly, rearwardly and laterally, means operated by the forward and rearward tilting for controlling the water motor and the flushing mechanism and a spring catch adapted to engage the tiltable back in its innermost position and to be disengaged therefrom by lateral tilting of the back rest.

Signed at Ottawa, Province of Ontario, this 30th day of July, 1907.

HARRY WILLIAMS CHARLTON.
